(57) **CLAIM**

The ornamental design for a portable front projection screen,
as shown and described.

DESCRIPTION

FIG. 1 is a front and top perspective view of the portable front
projection screen in a closed configuration showing our
design;

FIG. 2 is top view thereof;

FIG. 3 is a side view thereof;

FIG. 4 is a bottom view thereof;

FIG. 5 is an opposing side view of the side shown in FIG. 3;

FIG. 6 is a bottom end view thereof;

FIG. 7 is a top end view thereof;

FIG. 8 is a front perspective view of the portable front projection
screen shown in an open configuration;

FIG. 9 is a rear perspective view thereof;

FIG. 10 is a front perspective thereof;

FIG. 11 is a side view of the open embodiment shown in FIG.
8;

FIG. 12 is a rear view thereof;

FIG. 13 is an opposing side view of the view shown in FIG.
11;

FIG. 14 is a front view thereof;

FIG. 15 is a bottom view thereof; and,

FIG. 16 is a top view thereof.

The broken lines shown herein are for illustrative purposes
only and form no part of the claimed design.
